United States Patent Office

Des. 196,173
Patented Sept. 3, 1963

196,173

BUILDING

Al Lapin, Jr., North Hollywood, Calif., assignor to The International House of Pancakes Commissary, North Hollywood, Calif., a corporation of California

Filed Jan. 28, 1963, Ser. No. 73,351

Term of patent 14 years

(Cl. D13—1)

FIGURE 1 is a perspective view of a building, showing my new design;

FIGURE 2 is a top plan view with the lower right corner thereof shown fragmentarily for convenience of illustration only;

FIGURE 3 is a side elevational view;

FIGURE 4 is a front elevational view; and

FIGURE 5 is a rear elevational view.

The dominant features of my design reside in the portions shown in full lines.

I claim:

The ornamental design for a building, as shown and described.
